UNITED STATES PATENT OFFICE.

ADOLPH VON SCHLUEMBACH, OF ALTOONA, PENNSYLVANIA.

FOLDING CRATE OR BOX.

1,111,407.

Specification of Letters Patent. Patented Sept. 22, 1914.

Application filed July 8, 1912. Serial No. 708,117.

To all whom it may concern:

Be it known that I, ADOLPH VON SCHLUEMBACH, a citizen of the United States, residing at Altoona, county of Blair, and State of Pennsylvania, have invented certain new and useful Improvements in Folding Crates or Boxes, of which the following is a specification.

My invention relates to folding boxes or crates.

The primary object of my invention is to provide a box or crate which, when not in use, may be folded to occupy a minimum amount of space and which shall be of simple construction and of low cost to manufacture.

A further object of my invention is to provide a folding box or crate provided with partitions for dividing the same into upper and lower compartments, which partitions shall be adapted to fold as the box is collapsed or folded.

A further object of my invention is to provide a folding box or crate as mentioned in which the sides, when in open or distended position shall be flush with the edges of the top and bottom portions.

A further object of my invention is to provide a folding box or crate which shall be strong and durable, of great rigidity when in open position, and of comparatively light weight.

Other objects will appear hereinafter.

With these objects in view my invention consists generally in a box or crate comprising top and bottom frames, foldable sides connected at their upper and lower edges to said frames respectively, and end members hingedly connected to one of said frames and adapted to hold the sides in open position.

My invention further consists in a box or crate as mentioned together with partition members hingedly connected to said ends and adapted to divide the case, crate or box into upper and lower compartments.

My invention further consists in a device as mentioned in which the sides are so connected to the upper and lower frames as to lie in a plane or flush with the edges of said frame when the box or crate is in open position.

My invention further consists in a case, box or crate comprising top and bottom members, foldable sides having their edges hingedly connected to said members respec-

tively and interlocking devices on the top and bottom members and said sides adapted to coöperate when the device is in open or distended position to increase the rigidity 60 of the same.

My invention further consists in various details of construction and arrangements of parts all as will be fully described herein-after and particularly pointed out in the 65 claims.

My invention will be more readily understood by reference to the accompanying drawings forming a part of this specification and in which—

Figure 1 is a perspective view of a case, box or crate embodying my invention in its preferred form and illustrating the same in distended position, Fig. 2 is a perspective view of the same in folded position with the lid or cover raised, Fig. 3 is a vertical longitudinal section of the box or crate in distended position. Fig. 4 is a similar view of the same in folded position, Fig. 5 is a vertical transverse section on substantially the line $x-x$ of Fig. 3, the device being illustrated in partially folded position in dotted lines, Fig. 6 is a vertical transverse section on the line $y-y$ of Fig. 4, Fig. 7 is a horizontal section on the line $z-z$ of Fig. 4, Fig. 8 is a detail side elevation of one of the joints of the device, illustrating the interlocking devices, Fig. 9 is a view of the same at right angles to that of Fig. 8, Fig. 10 is a detail elevation of a modified form of joint, 80 Figs. 11 and 12, are details of a further modified form of joint, and Fig. 13 is a detailed sectional view of a further modification.

My invention as hereinafter described, 95 may be employed in making boxes, crates, show-cases, trunks and various other receptacles, but in the drawings I have illustrated the same as applied to folding boxes and crates, other uses of the invention being clear from the drawings and description to anyone skilled in the arts. Irrespective of the application of the invention, the general structure will be the same, the device in any event comprising upper and 100 lower members, foldable sides connecting said members and hinged ends adapted to hold the device in extended position.

Referring now to the drawings 1 indicates the upper or top member, and 2 the lower 110 or bottom member. These are connected as will be hereinafter described, by foldable

sides 3, and hinged ends 4 are provided to complete the body of the structure and hold the same in distended position. The top and bottom members preferably comprise frames formed of a pair of longitudinal members 5—5, a pair of transverse members 6—6 rigidly connected at the corners as by angle irons or braces 7, and panels 8 and 9 respectively. The panel 8 is hingedly connected as at 10 to the top frame and constitutes a lid or closure for the device, a turn button 11 or other suitable device being provided to fasten the same in closed position. The panel 9 is preferably rigidly secured to its respective frame and constitutes the bottom of the box or case.

The sides 3 are formed of two similar, upper and lower sections 12 and 13, hingedly connected at their abutting edges as at 14 so as to fold inwardly at the center, and hingedly connected as at 15 to the upper and lower members 1 and 2 respectively. The side sections, 12 and 13, are preferably formed of frames consisting of longitudinal members 16 and vertical members 17, and panels 18, the latter of which may be of any desired material, such as wood, netting or glass, according to the use to which the device is to be put. The end members 4 may be either solid, or framed and paneled as desired, no claim being made to the specific construction of this portion of the device, and they are hingedly connected as at 19 to the transverse or end members 6 of the lower or bottom member 2. The hinges 19 are arranged on the inner face of the member 6 and adjacent the lower portion thereof so that the ends shall fold down close to the bottom 9. If the box or 40 crate is comparatively deep the ends 4 will overlap when the device is collapsed, and in order that the ends shall lie flat when in folded position, I prefer to arrange the hinges 19 of one end slightly above or at a 45 slightly greater distance from the bottom than those of the other end. This construction will be clear by reference to Fig. 4. The sides 3 are hingedly connected to the members 5 so that when the device is expanded the edges of the sides will abut the edges of said members with the outer faces of the sides flush with the outer edges of the top and bottom members. When the sides are unfolded or extended, and the ends 55 raised into operative position, the edges of said ends engage the inner faces of the sides adjacent the ends and hold said sides in position.

To give greater rigidity to the structure 60 the abutting edges of the side sections, and the upper and lower edges of the sides and the adjacent edges of the members 5 are provided with interlocking members. In Figs. 8 to 13 inclusive I have illustrated various 65 forms of this portion of the device. In

Figs. 8, 9, 10 and 13 the adjacent edges are provided with pins 20 and sockets 21 respectively, and in Figs. 11 and 12 they are provided with tongues 22 and grooves 23 respectively. The interlocking members 70 may be formed directly upon the frame members of the sides or may be formed upon metal plates 24 and secured to the sides as illustrated in Fig. 13. To give further rigidity to the device the members 5 75 of the bottom portion are recessed as at 25 and the vertical members 17 of the adjacent side section are extended downwardly as at 26 to fit therein. The side sections may be connected to the upper and lower members 80 and to each other by any suitable hinge means, such as strap hinges as illustrated in Figs. 1, 3, 4, 5 and 6, or by knuckle joints 27 as illustrated in Figs. 8 and 9. If preferred the vertical members 17 of the side 85 sections may be connected by means of a pair of links 28, pivotally connected to both members as illustrated in Fig. 10.

Hingedly connected to the ends 4 as at 29 are members 30 which together form a horizontal partition dividing the device into upper and lower compartments. These are each a little longer than half the length of the box or crate and their inner ends overlap when the device is expanded and are supported by ears or brackets 31 secured to the inner faces of the sides 3 adjacent the center. Inasmuch as the ends 4 fold downwardly into the bottom member of the crate it is necessary to provide means whereby the partition members 30 may pass the brackets 31. To this end said members are provided at their edges with notches or recesses 32 which are arranged toward the ends 4 to which the respective partition members are connected. By this construction, as the ends are folded inwardly and downwardly, the partition members 30 will slide along the brackets 31 until the recesses 32 approach or reach said brackets when the partitions will readily pass the brackets and fold into the bottom of the device with the ends. If the ends are of sufficient length to engage the brackets 31 when folding inwardly, which is determined by the relative 110 height of the device, said ends may be recessed or notched as at 33 to permit the same to pass the brackets.

In constructing the device I prefer that the members 5 and 6 of the bottom portion shall be of equal height, forming with the bottom 9 a shallow receptacle into which the ends and partitions shall fold. The members 5 of the upper or top portion are of less depth than the end members 6 thereof 112 so that the sides 3 may fold into the upper or top portion as shown clearly in Figs. 4 and 6. Suitable fastening devices 34 are provided for securing the device in folded or collapsed position and handles 35 may 113

be provided to facilitate handling the device when either in folded or expanded position.

Having described my invention what I claim as new and desire to secure by Letters Patent is:

5. 1. In a device of the class described, upper and lower members, foldable sides having connections with said members, end pieces having connections with one of said members, and partition members connected with said end pieces, substantially as described.
10. 2. In a device of the class described, upper and lower members, foldable sides having connections with said members, end pieces having pivotal connections with one of said members, partition members having pivotal connections with said end pieces, and means for supporting the inner ends of said partition members.
15. 3. In a device of the class described, top and bottom members, foldable sides connected to said top and bottom respectively, end pieces hingedly connected to said bottom, partition members hingedly connected to said end pieces, and means for supporting the inner ends of said partition members, the edges of said members being recessed to pass said supporting means as said end pieces are swung inwardly.
20. 4. In a device of the class described, upper and lower members, foldable sides having pivotal connections with said members, end pieces disposed between said foldable sides and having hinged connections with the lower member, partition members hingedly connected to said end pieces intermediate the ends thereof, the inner ends of said partition members overlapping and brackets fixed to said foldable sides for supporting said overlapping ends.
25. 5. In a device of the class described, upper and lower members, foldable sides hingedly connected to said members and comprising vertical and transverse frame elements and panels between said elements, the vertical frame elements extending beyond the transverse elements at the lower edge and the adjacent part of said lower member being recessed to receive said ends, said ends being adapted to move into and out of said recesses as the box is expanded and folded respectively, and end pieces arranged between said sides and hingedly connected to one of said members, substantially as described.
30. 6. In a device of the class described, upper and lower members, foldable sides hingedly connected to said members and comprising vertical and transverse frame elements and panels arranged between said elements, the vertical frame elements extending beyond the lower transverse frame element and the adjacent portion of the said lower member being recessed to receive said ends, said ends being adapted to move into and out of said recesses as the box is expanded and folded respectively, interlocking devices on said projecting ends and said lower member adapted to operatively engage when the device is expanded, similar interlocking devices on the upper edge of said sides and said upper member, and end pieces arranged between said members and hingedly connected to one of the first mentioned members, substantially as described.
35. In testimony whereof I have signed my name to this specification in the presence of two subscribing witnesses.

ADOLPH VON SCHLEHENBACH.
